(57) **CLAIM**

The ornamental design for a loop for compression stocking, as shown and described.

DESCRIPTION

FIG. 1 is a left side perspective view of the loop of the claimed design in use;

FIG. 2 is a right side perspective view of the loop of the claimed design;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines showing a stocking in FIG. 1 depict environment and form no part of the claim. The dash dot dash broken lines depict the claim boundary and form no part of the claim. The evenly dashed broken lines showing portions of a loop for compression stocking form no part of the claim.
